[57] **ABSTRACT**

An infrared camera tube uses an electron beam to scan its photoconductive sensitive surface and produce an output. In order to avoid background current which might be produced by the thermionic cathode of the tube, the cathode is located off-axis of the tube. Magnets are used to deflect the electron beam first toward and then parallel to the tube axis. The beam is then focused and deflected in the usual manner.

FIG. 1

FIG. 2

INFRARED VIDICON WITH OFF-AXIS ELECTRON GUN

BACKGROUND OF THE INVENTION

Various types of infrared detectors are known in the art. These types include electronic scanning types such as orthicons and vidicons. A difficulty arise, however, with a scanning detector using an electron beam. The thermionic cathode from which the electron beam arises, if not shielded from the infrared sensitive surface, would produce a false output signal. One solution for this difficulty is shown on page 294 of the book *Elements of Infrared Technology* by Paul W. Kruse et al., New York, 1963. This book bears Library of Congress Catalog Card Number: 62-8776. The instant invention is a vidicon of more conventional construction than shown by Krause et al. Other solutions are those shown in U.S. Pat. Nos. 2,928,971, 2,947,896 and 3,014,148, respectively issued Mar. 15, 1960, Aug. 2, 1960 and Dec. 19, 1961.

SUMMARY OF THE INVENTION

The invention is an infrared vidicon having an electron gun offset from the longitudinal axis of the vidicon. Magnets are employed to bend the electron beam toward, then coaxial with the longitudinal axis. The infrared photoconductive sensitive surface of the vidicon is thus shielded from infrared energy emitted by the thermionic cathode of the electron gun.

BRIEF DESCRIPTION OF THE DRAWINGS

FIG. 1 shows a schematic side section of the invention.

FIG. 2 shows a sectional end view of the invention, taken in the direction as indicated in 2—2 in FIG. 1.

DETAILED DESCRIPTION OF THE INVENTION

The invention may be best understood by reference to the drawings. FIG. 1 shows a schematic side view of the invention in which 10 designates the glass envelope, with connecting pins 11 and infrared photoconductive sensitive surface 12. The electron gun includes cathode 13 with heater 14, and elements G₁, G₂, and G₃. As can be seen, the cathode and heater and G₁ and G₂ are off-axis from envelope 10. Element G₃ is perforated at 15 and 16 for entry and exit of the electron beam. The path of the electron beam is shown by dotted lines and is first bend toward the longitudinal axis of 10 by magnet 17, and then parallel to this axis by magnet 18. Each of 17 and 18 have pairs of pole pieces 19. As can

be seen more clearly in FIG. 2, magnets 17 and 18 are electromagnets with windings connected to a D-C source (not shown). Although the connections are not shown in the drawings, elements G₁, G₂, and G₃ would be connected to respective ones of pins 11. The usual alignment coil 20 and deflection and focusing coil 21 are shown and have their usual connections (not shown). Also shown is the system whereby an output is taken: i.e., D-C power source B and load resistor R_L connected between cathode 13 and sensitive surface 12.

While a specific embodiment of the invention has been shown and described, other embodiments within the scope of the invention may be obvious to ones skilled in the art. For example, magnets 17 and 18 may be permanent magnets, adjustable in position. The magnetism of electromagnets 17 and 18 may be adjusted to properly deflect the electron beam by varying the current through the coils of 17 and 18.

The cathode of the inventive vidicon is therefore not visible from sensitive surface 12, but the electron beam from the cathode can reach 12. It may be necessary to blacken in interior of G₃ in order to avoid the reflection of energy from 13 toward 12. Although not heretofore mentioned, 12 may be cooled in the usual manner, as shown in the book mentioned above in the Background of the Invention.

I claim:

1. An infrared vidicon having an elongated sealed envelope with a central longitudinal axis and with an electron gun in one end and an infrared sensitive surface in the other end, and electron beam deflection means:

said electron gun including a thermionic cathode, at least one control grid, and having a longitudinal axis parallel to but offset from the longitudinal axis of said envelope,

said vidicon further including electron beam bending means including means for deflecting the beam from said gun first toward and then coaxial with the longitudinal axis of said envelope.

2. The vidicon as defined in claim 1 wherein said electron beam bending means includes a pair of magnets.

3. The vidicon as defined in claim 2 wherein said magnets are electromagnets.

4. The vidicon as defined in claim 3 where the final beam forming member of said electron gun has an off-axis perforation and an axial perforation.
